UNITED STATES PATENT OFFICE.

CHARLES R. ROGERS, OF NEW YORK, N. Y., ASSIGNOR TO THE BRUNSWICK-BALKE-COLLENDER COMPANY OF NEW YORK, OF NEW YORK, N. Y., A CORPORATION OF NEW YORK.

REFRIGERATOR.

1,034,650.

Specification of Letters Patent.

Patented Aug. 6, 1912.

Application filed June 18, 1909. Serial No. 502,961.

To all whom it may concern:

Be it known that I, CHARLES R. ROGERS, a citizen of the United States, residing at New York, county of New York, and State of New York, have invented certain new and useful Improvements in Refrigerators, fully described and represented in the following specification and the accompanying drawings, forming a part of the same.

10 This invention relates to certain improvements in refrigerators.

One of the objects of this invention is to produce an improved construction of interior fittings for refrigerators of such a character that they may be readily removed to permit the interior of the refrigerator as well as the fittings to be thoroughly cleansed.

20 A further object of the invention is to produce interior fittings for refrigerators which may be readily removed therefrom and which are secured in place in such a way as to make it unnecessary to perforate the lining of the refrigerator by screws or 25 other devices, or by attaching to the lining supporting devices which cannot be readily cleaned, and which when attached to the walls are liable to form crevices or angles in which dirt may readily collect.

30 A further object of the invention is to produce an improved construction of interior fittings which may be readily knocked down for convenience in shipping.

With these and other objects not specifically referred to in view, the invention consists in certain constructions, and in certain parts, improvements and combinations as will be hereinafter fully described and then specifically pointed out.

40 Referring to the accompanying drawings—Figure 1 is a perspective view of a refrigerator constructed in accordance with the invention, certain parts being broken away to show the interior construction.

45 Fig. 2 is a plan view of the construction shown in Fig. 1. Fig. 3 is a vertical section taken on the line 3—3 of Fig. 4. Fig. 4 is a section on the line 4—4 of Fig. 3. Fig. 5 is a horizontal section on the line 5—5 of Fig. 3. Figs. 6 and 7 are detail views. Fig. 50 Fig. 8 is a perspective view of certain parts of the fittings removed from the refrigerator.

In the accompanying drawings which illustrate one embodiment of the invention,

the refrigerator casing is of the usual knock-down type, the sides, rear wall, top and bottom being connected together by screws, as usual, so that by removing the screws the structure may be knocked down and shipped flat. The front wall of the casing is, in the particular construction illustrated, formed by doors 1, 2 and by sills 3, 4 and 5, as usual in such constructions. The interior lining, in the particular construction illustrated, consists of a crock 6 or a single piece structure that is open at the front, but it is to be understood that the invention is not confined to refrigerators employing linings of the character shown.

Constructions embodying the invention will include an interior support which is detachably connected to the interior of the refrigerator. While this support may be variously constructed and arranged, in the form illustrated it comprises a piece of channel or angle iron bent to form a front cross-piece 7 and side pieces 8. One flange of the angle iron, in the construction illustrated, is cut away along that part which forms the front piece 7, but is left intact along the side pieces 8 so as to form rests 9 on which a shelf or receptacle may be placed, if desired. If desired, furthermore, these flanges may be bent up to form stops 10 to prevent any rearward movement of 85 the shelf or receptacle.

The support will be detachably connected to the wall of the refrigerator and this connection may be effected in various ways. In the particular construction illustrated, the support is detachably connected to the sill 4 which forms a part of the front wall by means of a clip consisting of a pair of U-shaped pieces 11, these pieces being connected to the sill by means of screws, as 12 or in any other suitable manner. This form of connection is simple and cheap and enables the support to be readily removed. Further, the attachment to the sill renders it unnecessary to attach any supporting devices to the lining of the refrigerator, making it unnecessary to perforate the lining, thereby especially adapting it to use with refrigerators having a single piece or integral lining.

In the particular construction illustrated, the horizontal support referred to is steadied and additional strength is provided by con-

necting to said support a brace. While this brace, when employed, may be variously disposed, in the construction illustrated, it comprises a pair of bars 13 pivoted at 14 to 5 the vertical sides of the angle iron support, and detachably connected to the same wall of the refrigerator to which the support is connected. In the particular construction illustrated, the attachment is effected by 10 providing the upper ends of the brace bars with perforations 15 which are caused to engage with hooks 16 fastened to the sill 3 of the refrigerator.

In the particular construction illustrated, 15 the horizontal support referred to carries the ice chamber 17, the bottom of this chamber resting upon the parts 9 of the angle iron. The usual ice support 18 is shown in connection with this ice chamber. The ice 20 chamber may be conveniently and cheaply made of metal, such as galvanized iron, as is usual. In order to prevent the ice chamber from being tipped and thereby possibly chipping and defacing the interior lining 25 of the refrigerator, guards, as 19, which consist of bent metal strips attached to the brace bars 13 may be provided. These guard strips will also act, if employed, as guides so that the ice chamber may be readily 30 slipped into place without coming in contact with the interior lining of the refrigerator. These guards when employed, may be attached to the brace bars by bolts 19', or in any other suitable manner, the attachment 35 preferably being of such a character that the guards may be arranged parallel with the brace bars when the construction is to be knocked down.

Constructions embodying the invention 40 may also employ a vertically disposed support extending from the horizontal support to the floor of the refrigerator, and when this support is employed it will be detachably connected to the floor and horizontal 45 support. While this support, when employed, may be varied, in the particular construction illustrated it comprises four vertical bars 20. The detachable connection with the floor and the support may be effected in various ways. As shown, the detachable connection with the support is effected by providing the rearwardly extending arms thereof with loops 21 which may be conveniently and cheaply formed by striking 55 and punching them out of the metal of the arms, and the upper ends of the bars are shouldered, as illustrated, to provide tongues or projections 22 which engage the loops. While the detachable connection with the 60 floor may be effected in various ways, as shown, the floor is provided with dowels 23 which when, as in the construction illustrated, the lining consists of a single molded piece or crock, may be conveniently inserted during the formation of the crock. 65

As shown, the lower ends of the bars are bent at right angles to form projections 24 which are perforated to engage the dowels.

The vertical support employed may be utilized not only for sustaining the horizontal support but also as a shelf support. While this may be accomplished in various ways, in the particular construction shown the bars are provided with struck out projections 25 on which the usual wire racks, indicated at 26, rest and with which they engage. The usual drain pipe 27 is illustrated leading from the ice chamber through the bottom of the refrigerator underneath which a drip pan may be placed, as usual.

The construction of interior fitting described is readily removable from the interior of the refrigerator, so that both it and the interior may be readily cleaned. Further, it is not necessary to employ with it any brackets or lugs secured to the lining of the refrigerator, so that the lining is not perforated, and, further, no sharp angles are formed in which dirt can collect. The only attaching devices in the wall of the lining 9 are the dowels referred to and they are of such a character that if any dirt collects around them, it can be readily wiped off. Further, the interior fitting can be knocked down and shipped flat. This is a great advantage, especially where refrigerators are made in factories in large quantities and shipped knocked down to be set up at the place where they are used or sold.

Changes and variations may be made in 10 the construction by which the invention is carried into effect. The invention is not, therefore, to be confined to the particular details of construction herein described and illustrated in the accompanying drawings. 10

What is claimed is:—

1. In a refrigerator, the combination with a horizontally disposed support including side bars, said support being detachably connected to the interior of the refrigerator, of a support comprising a plurality of bars resting on the floor of the refrigerator and detachably connected to the floor and to the side bars.

2. In a refrigerator, the combination with a casing having a door in one side, of a horizontally disposed support including side bars detachably connected to the interior of the refrigerator, a vertically disposed support extending from and detachably connected to the refrigerator floor and to the side bars, said vertically disposed support being permanently located at the sides of the refrigerator when in position therein and being provided with shelf supporting devices.

3. In a refrigerator, the combination with a horizontally disposed support including side bars detachably connected to the interior of the refrigerator, of vertically dis-

posed supporting bars extending from and detachably connected to the refrigerator floor and to the horizontal bars, said vertical bars being permanently located at the 5 sides of the refrigerator when in position and being provided with shelf supporting devices.

4. In a refrigerator, the combination with a casing having a door at one side, of an 10 interior lining open at the front, a horizontally disposed support including four bars detachably connected to the casing and extending along the sides of the refrigerator, and vertically disposed supporting bars de- 15 tachably connected to the horizontal bars and extending from them to the refrigerator floor, said vertically disposed bars being permanently located at the sides of the refrigerator when in position and carrying 20 shelf supporting devices.

5. In a refrigerator, the combination with a horizontally disposed support detachably connected to the interior of the refrigerator, of sockets on the support, vertically dis- 25 posed bars engaging the sockets on the support, and means for detachably connecting the bars to the floor of the refrigerator.

6. In a refrigerator, the combination with a casing, of an interior lining open at the 30 front, a horizontally disposed support detachably connected to the casing at the front of the refrigerator and extending into the refrigerator, sockets in the support, vertically disposed bars engaging the sockets and 35 extending to the floor of the refrigerator, and means for detachably connecting the bars to the refrigerator floor.

7. In a refrigerator, the combination with a casing, of an interior lining open at the 40 front, a clip on the interior of the casing at the front, a horizontal support engaging the clip, and a vertical support extending from and detachably connected to the horizontal support and the floor of the refrigerator.

45 8. In a refrigerator, the combination with an exterior casing, of an interior lining open at the front, a clip connected to the interior of the casing at the front, an angle iron support arranged to engage the clip, 50 sockets in the support, vertically disposed supporting bars extending from the support to the floor of the refrigerator, and means for detachably connecting the bars to the floor.

55 9. In a refrigerator, the combination with a casing, of a lining open at the front, a

horizontally disposed support detachably connected to the front wall of the refrigerator and extending into the interior of the refrigerator, and a brace comprising two 60 angularly disposed members attached to the support and detachably connected to the same wall.

10. In a refrigerator, the combination with a horizontally disposed support detach- 65 ably connected to a wall of the refrigerator, of a brace attached to the support and detachably connected to the same wall of the refrigerator, and a vertically disposed sup- 70 port extending from and detachably connected to the refrigerator floor and the horizontal support.

11. In a refrigerator, the combination with a refrigerator casing, of an interior lining open at the front, a horizontally dis- 75 posed support connected to the front wall of the refrigerator and extending into the interior of the refrigerator, a brace comprising a pair of angularly disposed members attached to the support and detachably connected to the front wall of the refrigerator, and vertically disposed bars extending from and detachably connected to the refrigerator floor and the horizontal support.

12. In a refrigerator, the combination with an angle iron support detachably connected to the wall of the refrigerator, of a brace comprising a pair of angularly disposed bars connected to the angle iron and detachably connected to the wall of the re- 90 frigerator which supports said angle iron, and a vertical support extending from and detachably connected to the horizontal support and the floor of the refrigerator.

13. In a refrigerator, the combination with an angle iron support detachably connected to the wall of the refrigerator, of a brace comprising a pair of angularly disposed bars connected to the angle iron and detachably connected to the wall of the 100 refrigerator which supports said angle iron, and a vertical support comprising a plu- 105 rality of bars extending from and detachably connected to the horizontal support and the floor of the refrigerator.

In testimony whereof, I have hereunto set my hand, in the presence of two subscribing witnesses.

CHARLES R. ROGERS.
